CHARGE FORMING DEVICE

Wilford H. Teeter, Dayton, Ohio, assignor to
Delco Products Corporation, Dayton, Ohio, a
corporation of Delaware

Application August 19, 1929. Serial No. 387,008

15 Claims. (Cl. 123—52)

This invention relates to charge forming devices for internal combustion engines and more particularly to devices of this character which comprise a plurality of primary carburetors which deliver a primary mixture of fuel and air to a plurality of secondary mixing chambers located adjacent the engine intake ports and in which the primary mixture is mixed with additional air under certain operating conditions.

10 Devices of this general character are disclosed in the copending application of Fred E. Aseltine, Wilford H. Teeter and Carl H. Kindl, Serial No. 288,683, filed June 27, 1928.

15 It is the principal object of the present invention to provide in a device of the character above described, means to secure a more equal distribution of the fuel charge to the cylinders of a multicylinder engine. More specifically, it is the object of the present invention to construct the 20 manifold which forms part of a charge forming device of this character in such a manner that the engine suction communicated to any one branch of the manifold when the intake valve of that particular branch is open is not directly 25 communicated to certain other branches and surging of the mixture from one outlet branch to the other as the engine suction is directly communicated to these branches, is largely prevented.

30 In the embodiment of the invention disclosed herein a charge forming device for an eight cylinder engine is illustrated, the invention being particularly adaptable to an engine of that type.

According to the present invention as disclosed herein the distribution difficulties with an 35 eight cylinder engine have been substantially eliminated by providing two conduits within the manifold both of which communicate with a single intake and each of which is constructed 40 to communicate directly with the intake ports of a group of four cylinders, the construction being such that the eight cylinder engine is really divided into two four cylinder engines having the same firing order, the intake ports of 45 each of which communicate directly with one of said manifold conduits.

Further objects and advantages of the present 50 invention will be apparent from the following description, reference being had to the accompanying drawings, wherein a preferred embodiment of one form of the present invention is clearly shown.

In the drawings:

55 Fig. 1 is a vertical, longitudinal section through

a charge forming device constructed in accordance with the present invention.

Fig. 2 is a horizontal section through the manifold of Fig. 1, certain parts being shown in plan.

Fig. 3 is a top plan view.

Fig. 4 is a fragmentary front elevation of the manifold which forms a part of the charge forming device.

Fig. 5 is a fragmentary section on the line 4—4 of Fig. 1.

The device disclosed comprises a main manifold 10 having four outlet branches 12, 14, 16 and 18, as disclosed in Fig. 2. Each of these branches communicates with one of the intake ports 20 of an eight-cylinder engine. These branches are each provided with an attaching flange 22 for securing the manifold to the engine block in the usual manner, and a flange 24, to which the carburetor unit is secured.

The carburetor unit comprises a main housing 26, having an attaching flange 28 adapted to be secured to the flange 24 by screws 30. An air inlet coupling 32 is secured in position to register with an opening in the upper wall of the housing 26 in any suitable way, and may be connected with an air cleaner if desired. A casting 34 in which the passages supplying fuel to the nozzles are formed, is secured by screws to the lower wall of the main housing and a sheet metal fuel bowl 36 is held tight against an annular shoulder 38 on the housing by any suitable means. Fuel is conducted from a main source of supply to the fuel bowl through a conduit (not shown) and the flow is controlled by a float 40 operating in the usual manner to maintain a substantially constant level of fuel therein.

Fuel flows from the bowl 36 to a plurality of primary fuel nozzles 42, one of which is located in each of the primary mixing chambers 44, the construction of which is briefly described hereinafter. The fuel conduit between the fuel bowl and the nozzles comprises the vertical fuel passage 46 communicating at its upper end with a horizontal fuel canal 48, which communicates with each of the nozzles 42 through an orifice 50. Fuel is admitted from the fuel bowl to the passage 46 at all engine speeds through a fixed metering orifice 52, and at high speeds additional fuel is admitted through an orifice 54 controlled by a valve 56, operated in the manner set forth in the above mentioned application. The nozzles supply fuel to the primary mixing chambers in the manner described in the above application and each nozzle is provided with a fuel metering orifice 58.

The primary mixing chambers comprise the enlarged anterior ends of the primary mixture passages 60, which are parallel to each other and close together, as indicated in Fig. 2. When the carburetor is attached to the manifold these passages register with conduits which convey the primary mixture to the secondary mixing chambers as briefly described hereinafter. Restrictions 62 separate the primary mixing chambers from the remainder of the mixture passages to reduce the velocity flow past the fuel nozzle for a purpose fully set forth in the above application.

A single throttle valve 64, which extends across all the primary mixture passages, controls the flow therethrough and is provided with grooves 66 which register with said mixture passages. The primary mixture passages communicate with conduits which extend to the secondary mixing chambers in the outlet branches of the manifold. These conduits comprise passages 68, formed in the manifold casting, as indicated in Fig. 2 and pipe connections 70 which communicate with the passages 68 and are connected by elbows 72 to tubes 74 which are fixed in position in the manifold and are coaxial with each outlet branch. Except for the fact that there are four of the primary mixture conduits disclosed in this device, such conduits are of substantially the same construction as those fully described in the above application and no more detailed description of these conduits need be incorporated herein.

Nearly all of the air entering the carburetor flows through the inlet coupling 32, and is controlled by main air valve 76, normally held against a seat 78 by a spring 80, received between the valve and a flange 82 projecting from a sleeve 84, slidably mounted on a stationary guide sleeve 86, fixed in the main housing and serving also as a guide for the stem 88 to which the air valve 76 is secured. To facilitate starting of the engine, the flange 82 may be lifted by means not shown herein but fully described in the above application, until the upper end of the sleeve 84 engages the air valve to hold it closed. Sufficient air to carry the starting fuel from the nozzles to the intake ports is admitted through an elongated slot 90, formed in a plate 92, secured to the main housing as shown in Fig. 1.

The valve 76 admits air to the air chamber 94 from which air flows to the primary mixture passages through an opening 96 in the bottom of the air chamber and to the secondary mixing chambers through a passage 98, which connects with the inlet of the manifold 10. A manually operable throttle 100 is secured to a shaft 102, rotatably mounted in the housing and a suction operated valve 104 secured to a shaft 106, also rotatably mounted in the housing control the flow of air through the passage 98.

The valve operating mechanism forms no part of this invention and it is sufficient for the purposes of this disclosure to describe very briefly the mode of operation of these valves. The primary throttle 64 is connected to the throttle 100 by an adjustable lost motion connection which is generally adjusted to permit the primary throttle to move without the accompanying movement of the air throttle until the former reaches a position corresponding to a vehicular speed of approximately 15 to 20 miles per hour on the level after which the two throttles are moved simultaneously. The valve 104, which is operated by engine suction, is opened only after the valve 100 begins to open and is retarded during its opening movement for the purpose of improving the oper-

ation of the engine during the acceleration period, as fully set forth in the above-mentioned application.

The opening of the main air valve 76 is also retarded to prevent fluttering of the valve and to prevent the admission of enough air to dilute the mixture. For this purpose a dashpot is provided comprising a cylinder 108, formed in the casting 36, and a piston 110, secured to the lower end of the valve stem 88 by any suitable means. This dashpot is of conventional form and its specific construction is not material to the present invention. The above described dashpot is also constructed to serve as a fuel pump in the device disclosed. To this end a delivery conduit 112 is provided which extends from the dashpot cylinder 108 to a horizontal channel 114, formed in a block 116, secured to the bottom of the main housing, and provided with four vertical passages 118, each of which communicates with one of the mixture passages as fully set forth in the above application. The pump is not a part of this invention and reference may be had to the above application for a complete disclosure thereof.

According to this invention the intake manifold 100 is provided with a single air inlet passage 120, which communicates with the passage 98, referred to above. The passage 120 communicates with two horizontal passages 142 and 144 respectively, directly connecting with the manifold outlet branches 12 and 18, 14 and 16 respectively, as clearly shown in Fig. 3. The outlet branches 12 and 18 communicate with two intake ports which supply cylinders 1, 2, 7, and 8 with combustible mixture, while the outlet branches 14 and 16 supply cylinders 3, 4, 5 and 6 with fuel mixture. Thus it will be seen that the passage 142 supplies fuel mixture to a group of four cylinders of an eight-cylinder engine, while passage 144 supplies mixture to another group of four cylinders of said 115 engine, and these cylinders are so arranged that the firing order of the two groups is the same.

In order to explain the operation of this invention it is necessary to consider what happens in the ordinary intake manifold of an eight cylinder engine having the cylinders in line. The firing order of such an engine may be 1, 6, 2, 5, 8, 3, 7, 4, and in an intake manifold of the type disclosed which has four outlet branches, said branches each supply two ports, 1, 2; 3, 4; 5, 6; and 7, 8. 125 When the intake valve associated with any one cylinder is open the engine suction is communicated to some extent to every outlet branch of a conventional manifold, and where primary fuel mixture is delivered to the outlet branches, as in 130 charge forming devices of the type disclosed, fuel collects in any one outlet branch as all other outlet branches are effective until the valve associated with that particular branch is opened, when such collected fuel is drawn into the engine. 135 When the firing order is as indicated above there must be unequal distribution of fuel to the various ports. For instance, considering ports 1 and 2, there is only one cylinder, 6, which fires between 1 and 2 while there are five cylinders which fire 140 between 2 and 1. Therefore, because of the above described accumulation of fuel in the manifold branch supplying cylinders 1 and 2 during the firing of other cylinders, it will be obvious that the fuel charge delivered to cylinder 1 is greater than 145 that delivered to cylinder 2. It will be clear, however, that in the device disclosed, each of the passages 122 and 124 supply mixture to a group of four cylinders, the firing order of which is such that one cylinder is fired between any two so that 150

the supply of fuel to every cylinder is substantially the same.

Although the two passages 122 and 124 are in communication at the point where they connect with the passage 120 there is a partition 130 which partially separates the two passages 122 and 124 and the effect of this partition and of the air entering the passage 120 is such that the suction communicated to the outlet branches 14 and 16, when the intake valves associated with such branches are open, is not communicated to the outlet branches 12 and 18 sufficiently to be noticeable. Since this is true and since the passages 122 and 124 are in direct communication with only four cylinders instead of eight, it will be obvious that there will be less surging of the fuel mixture back and forth from one outlet branch to another than in a manifold of conventional form comprising one passage having outlet branches communicating with all the engine intake ports.

The secondary mixing chambers comprise Venturi tubes 132 positioned adjacent the outlet ends of the primary mixture conduits in all the outlet branches. These tubes are identical and each is provided with an exterior rib 134, which is adapted to be clamped between shoulders 136 and 138 on the manifold of the engine block respectively, when the device is assembled. These tubes accelerate the flow of air past the delivery ends of the primary mixture conduits, increasing the velocity of flow therethrough in the manner set forth in the above-mentioned application.

The specific details of construction of the carburetor unit are not material so far as the present invention is concerned, and any carburetor unit of the general type shown may be substituted for that above described.

While the form of embodiment of the present invention as herein disclosed, constitutes a preferred form, it is to be understood that other forms might be adopted, all coming within the scope of the claims which follow.

What is claimed is as follows:

1. A charge forming device for multi-cylinder internal combustion engines comprising a carburetor unit provided with means for forming a primary mixture of fuel and air and a manifold associated therewith which is adapted to supply a combustible mixture to the engine intake ports, said manifold having a plurality of air passages formed therein, each of which communicates with part only of the intake ports and means for supplying primary fuel mixture to each of said air passages.

2. A charge forming device for multi-cylinder internal combustion engines comprising a carburetor unit provided with means for forming a primary mixture of fuel and air and a manifold associated therewith which is adapted to supply a combustible mixture to the engine intake ports, said manifold having a plurality of air passages formed therein, each of which communicates with certain of said intake ports, secondary mixing chambers formed in said air passages and means for supplying primary mixture to said secondary mixing chambers.

3. A charge forming device for multi-cylinder internal combustion engines comprising a carburetor unit provided with means for forming a primary mixture of fuel and air, a manifold associated therewith which is adapted to supply a combustible mixture to the engine intake ports, said manifold being provided with a plurality of air passages each of which communicates with

certain of said intake ports only, means for supplying primary fuel mixture to said passages and a single air inlet adapted to admit air to both of said passages.

4. A charge forming device for multi-cylinder internal combustion engines comprising a carburetor unit provided with means for forming a primary mixture of fuel and air and a secondary air supply passage, a manifold associated therewith which is adapted to supply a combustible mixture to the engine intake ports, said manifold being provided with a plurality of air passages each of which communicates with certain of said intake ports only, and a single air inlet passage in said manifold communicating with both said air passages and the secondary air supply passage formed in the carburetor unit.

5. A charge forming device for multi-cylinder internal combustion engines comprising a carburetor unit provided with means for forming a mixture of air and fuel, an intake manifold associated therewith which is provided with a plurality of outlet branches adapted to communicate with the engine intake ports, means in said manifold to prevent surging of the charge from certain outlet branches to certain other outlet branches, and means for introducing the mixture of air and fuel formed in the carburetor unit directly into the outlet branches of the manifold.

6. A charge forming device for multi-cylinder internal combustion engines comprising a carburetor unit provided with means for forming a mixture of air and fuel, an intake manifold associated therewith which is provided with a plurality of outlet branches adapted to communicate with the engine intake ports, means dividing said manifold into a plurality of intake passages, each of which communicates directly with certain of the intake ports only whereby surging of the charge from certain outlet branches to certain other outlet branches, and means for introducing the mixture of air and fuel formed in the carburetor unit directly into the outlet branches of the manifold.

7. A charge forming device for an eight cylinder internal combustion engine comprising a carburetor unit provided with means for forming a mixture of air and fuel therein, a manifold associated therewith which is adapted to communicate with the engine intake ports, means within said manifold dividing it into a plurality of passages each of which communicates directly with the intake ports supplying combustible mixture to four cylinders, means for conveying fuel mixture from the mixture forming means to said passages, and an air inlet admitting air to said passages.

8. A charge forming device for an eight cylinder internal combustion engine comprising a carburetor unit provided with means for forming a mixture of air and fuel therein, a manifold associated therewith, which is adapted to communicate with the engine intake ports, means within said manifold dividing it into a plurality of passages each of which communicates directly with the intake ports supplying combustible mixture to a group of four cylinders, said groups of cylinders having the same firing order, means for conveying fuel mixture from the mixture forming means to said passages, and an air inlet admitting air to said passages.

9. A charge forming device for multi-cylinder internal combustion engines having a plurality of intake ports, comprising a plurality of primary

- mixing chambers each of which is adapted to supply primary mixture to an intake port, a single secondary air passage, an intake manifold having an inlet communicating with said secondary air passage, and a plurality of outlet branches communicating with said intake ports, means within the manifold for dividing it into a plurality of passages each of which communicates with only a portion of the outlet branches, and primary mixture conduits for conveying the primary mixture from said mixing chambers to the outlet branches of said manifold. 80
10. An intake manifold for a multi-cylinder internal combustion engine comprising a plurality of outlet branches adapted to communicate with the engine intake ports, an air intake passage, for admitting air to said manifold, a plurality of passages within the manifold each of which communicates with said air intake passage and with certain of said outlet branches only, and means for supplying primary mixture to said manifold for admixture with the air admitted thereto. 85
11. An intake manifold for a multi-cylinder internal combustion engine comprising a plurality of outlet branches adapted to communicate with the engine intake ports, an air intake passage for admitting air to said manifold, a plurality of passages within the manifold, each of which communicates with said intake passage and with certain of said outlet branches only and conduits communicating with each outlet branch of the manifold for supplying primary mixture thereto. 90
12. A charge forming device for multicylinder internal combustion engines comprising a carburetor unit provided with means for forming a mixture of fuel and air and a manifold associated therewith which is adapted to supply a combustible mixture to the engine intake ports, said manifold having a plurality of outlet branches adapted to communicate with all the engine intake ports, a plurality of passages formed within the manifold each of which communicates with certain of said outlet branches only, a single inlet for the manifold adapted to communicate directly with both of said passages and means for supplying a mixture of fuel and air directly to all of the outlet branches. 95
13. A charge forming device for multicylinder internal combustion engines comprising a carburetor unit provided with a plurality of primary mixing chambers, means for supplying fuel and air to said mixture passage, a single secondary air passage adapted to supply air for mixture with the primary fuel mixture, an intake manifold associated with said carburetor unit, said manifold having a plurality of outlet branches each of which communicates with one of the engine intake ports, a plurality of air passages within the manifold, each of which communicates directly with certain of said outlet branches only, a plurality of conduits conveying primary mixture from the mixing chambers to the outlet branches, and a single passage connecting all of said plurality of air passages with the secondary air passages of the carburetor unit. 100
14. A charge forming device for multicylinder internal combustion engines comprising a carburetor unit provided with a plurality of primary mixing chambers, means for supplying fuel and air to said mixture passage, a single secondary air passage adapted to supply air for mixture with the primary fuel mixture, an intake manifold associated with said carburetor unit, said manifold having a plurality of outlet branches each of which communicates with one of the engine intake ports, a plurality of air passages within the manifold, each of which communicates directly with certain of said outlet branches only, a plurality of conduits conveying primary mixture from the mixing chambers to the outlet branches, and a single passage connecting all of said plurality of air passages with the secondary air passages of the carburetor unit. 105
15. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 110
16. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 115
17. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 120
18. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 125
19. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 130
20. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 135
21. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 140
22. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 145
23. An intake manifold for a multicylinder engine having a plurality of intake ports, said manifold comprising a plurality of outlet branches adapted to communicate with the engine intake ports, a plurality of passages formed within the manifold, each of which communicates directly with certain of said outlet branches only, a single air inlet port adapted to supply air to both of said passages and conduits adapted to convey fuel mixture from a carburetor with which the manifold is designed to be associated to the outlet branches of said manifold. 150

WILFORD H. TEETER.
